UNITED STATES PATENT OFFICE.

LOUIS O. SJOSTROM AND MYRON D. SPENCER, OF MEYERS FALLS, WASHINGTON.

DITCH-FORMING MACHINE.

Application filed May 7, 1923. Serial No. 637,248.

To all whom it may concern:

Be it known that we, LOUIS O. SJOSTROM and MYRON D. SPENCER, citizens of the United States, residing at Meyers Falls, in 5 the county of Stevens and State of Washington, have invented a new and useful Ditch-Forming Machine, of which the following is a specification.

This invention relates to ditch forming machines and more particularly to a ditch forming machine wherein the scooping elements work laterally of the track on which the machine is positioned.

Another object of the invention is to provide means for receiving material from the scooping or digging element to carry the material to a point remote from the machine.

A still further object of the invention is 20 to provide means for adjusting the material carrying elements to cause the same to deposit material at various points.

With the foregoing and other objects in view which will appear as the description 25 proceeds, the invention resides in the combination and arrangement of parts and in the details of construction hereinafter described and claimed, it being understood that changes in the precise embodiment of the 30 invention herein disclosed, may be made within the scope of what is claimed, without departing from the spirit of the invention.

Referring to the drawings:

Figure 1 is a side elevational view of a 35 machine constructed in accordance with the invention.

Figure 2 is a sectional view taken on line 2-2 of Figure 1.

Figure 3 is a plan view of the machine.

Figure 4 is an enlarged detail view of the 40 mechanism for throwing the endless conveyor into and out of operation.

Figure 5 is a side elevational view of the machine.

Figure 6 is a sectional view taken on line 45 6-6 of Figure 1.

Referring to the drawings in detail, the body of the machine includes a pair of spaced side bars indicated at 5 to which the 50 platform 6 is secured, trucks 7 being mounted at each end of the body portion to support the body portion on the rails 8, it being understood that the wheels 9 operating on the rails 8, are mounted on the truck.

Mounted on the platform 6 are U-shaped 55 bearing members 10 disposed adjacent to the

side edges thereof, which bearing members accommodate the bearings 11 in which the shaft 12 operates, the bearings 11 being formed with curved securing rings 13 to 60 which the ends of the cable 14 are connected.

The digging elements are supported on the outer ends of shaft 12, as clearly shown by Figure 2 of the drawings, each digging element embodying a plurality of radiating 65 arms 15 to which the scoops 16 are secured, the scoops being of constructions to deliver material inwardly towards the body portion of the machine.

Keyed or otherwise secured to the shaft 70 12 at a point intermediate the ends of the shaft, is a sprocket wheel 17 over which the chain 18 operates, which chain also moves over the sprocket wheel 19 carried by shaft 20, so that movement of the shaft and 75 sprocket wheel 19 is imparted to the sprocket wheel 17 and shaft 12 to operate the digging elements.

Rotary movement is imparted to the shaft 80 20 by means of the gear 21 which is also mounted on the shaft 20, the teeth of the gear 21 being in mesh with the teeth of the pinion 22 operated by the connecting rod 23 of the engine 24, which in the present 85 showing is operated by steam pressure from the boiler 25. Supported under the platform 6 are the chutes 26 that lie in the path of travel of material deposited by the scoops 16. Operating under the inner ends of the 90 chutes 26 are the endless conveyors 27 that move over the rollers 28 mounted on the shaft 29 that has its ends supported in the bearings 30'.

Shaft 29 also supports sprocket wheel 30 that receives motion from the chain 31 operating over the sprocket 32 mounted on the shaft 33. This shaft 33 is adjustably supported in the elongated bearing 34 so that the same may be moved towards and away from the body portion of the machine.

Sprocket 35 is also mounted on shaft 33 and receives motion from the chain 18 that operates the digging elements. Thus it will be seen that as the sprocket 35 is moved into and out of contact with the chain 18, the 105 endless conveyors 27 are controlled to accomplish their purposes.

The reference character 36 indicates a rotatable support on which bearings 37 are positioned, which bearings accommodate shaft 38 over which the endless conveyor 39 operates. The endless conveyor 39 also

operates over the roller 40 mounted at the free end of the boom 41 which boom is designed to be moved laterally to direct material to the desired point of discharge.

- 5 A hopper 42 is supported at the inner end of the boom 41, which hopper is designed to receive material from the endless conveyors 27 and direct the same to the endless conveyor 39, it being understood that the outer 10 ends of the conveyors 27 are disposed above the hopper 42, as at 43 the intermediate portions of the conveyors being held in proper spaced relation with each other, by means of the rollers 44 and 45.
- 15 The rollers 44 and 45 are supported by the brackets 46 and contact with the upper surfaces of the endless conveyors at points adjacent to the side edges thereof so that the material deposited on the endless conveyor 20 27 may pass under the shafts supporting the rollers 44 and 45.

Supported on the platform 6 is a curved arm 47 which has its free end disposed directly over the digging elements and provides a support for the pulleys 48 and 49, the pulley 48 accommodating the cable 50 which also operates over a pulley 51 from where the cable passes over roller 52 and is wound on the drum 53 operated by the engine 54 controlled by a suitable means not shown. Clutch member 55 controls the movements of the drum 53. Since the pulley 51 has connection with the outer end of the boom 41, it is obvious that as the cable 50 is wound on the drum 53, the boom 41 may be adjusted and moved to various positions to discharge the material falling on the endless conveyors supported by the boom. Pulley 57 has connection with the cable 14,

the pulley being provided with a housing 40 formed with an eye 58 to which one end of the cable 59 is secured, the cable passing over roller 60 from where the same passes to the drum 61 controlled by means of the clutch member 62. This cable 59, when wound on its drum 61 will elevate the digging elements to move them to their inactive positions when it is desired to advance the machine.

In order that the endless conveyor 39 will operate, a suitable engine not shown, may be supported on the rotatable support 36 and connected with the shaft 38, so that when the boom 41 is operated, the platform or support 36 will also move carrying the 55 engine.

From the foregoing it will be seen that as the digging elements are operated, material will be directed to the endless conveyor 27 and 39 where they may be discharged.

What is claimed as new is:—

In a ditch forming machine, a wheel supported body, a curved arm extending upwardly from the body, a vertically adjustable shaft mounted on the body, digging elements carried by the shaft, means for rotating the digging elements, a cable having connection with the arm and having connection with the axle for raising and lowering the digging elements, and means for transmitting movement to the axle to rotate the digging elements.

In testimony that we claim the foregoing as our own, we have hereto affixed our signatures.

LOUIS O. SJOSTROM.
MYRON D. SPENCER.
